The ornamental design for a clock face, as shown and described.

DESCRIPTION

FIG. 1 is a front elevational view showing my new design; FIG. 2 is a front elevational view of a modified form of my new design;

FIG. 3 is a front elevational view of another form of my new design; and,

FIG. 4 is a front elevational view of yet another form of my new design.

The clock face is conventionally of no appreciable thickness, and the rear is flat and unornamented.
